Filed July 17, 1961, Ser. No. 65,957

Term of patent 7 years

(Cl. D26—14)

FIG.3

FIG. 1 is a side elevational view of a combined telephone dialer and call timer, showing my new design. FIG. 2 is a front elevational view thereof.

FIG. 3 is a top plan view thereof.

The shading shown on FIGS. 1 and 2 of the drawing is to indicate color contrast.

I claim:

The ornamental design for a combined telephone dialer and call timer, substantially as shown and described.
